UNITED SHOE MACHINERY COMPANY, OF PATERSON, NEW JERSEY, A CORPO-
RATION OF NEW JERSEY.

MACHINE FOR INSERTING FASTENINGS.

1,070,066.

Specification of Letters Patent.

Patented Aug. 12, 1913.

Application filed June 26, 1909. Serial No. 504,588.

To all whom it may concern:

Be it known that we, WILLIAM PRATT and GERALD PEGG, subjects of the King of England, residing at Leicester, in the county of 5
Leicester, England, have invented certain Improvements in Machines for Inserting Fastenings, of which the following description, in connection with the accompanying drawings, is a specification, like reference 10 characters on the drawings indicating like parts in the several figures.

An object of this invention is to provide improved guiding and separating means, which are especially adapted for delivering 15 fastenings to the inserting mechanisms in machines for inserting previously formed fastenings, although it will be obvious that such means may also be used to advantage in other connections.

More particularly, the invention aims to 20 improve the construction and operation of machines of the type known as "loose nailers" whereby such machines may be fitted for use with nails of peculiar or special 25 shapes, such as nails used for ornamenting the soles or heels of boots and shoes.

When it has been attempted to use the ordinary loose nailing machine to drive nails which are oblong or rectangular in cross- 30 section and which have heads the dimensions of which lie parallel to those of the cross-section of the shank, difficulty has been experienced in separating the endmost nail from the others in the line in the raceway 35 and delivering it to the inserting mechanism, particularly when the heads of the nails are not much larger than the shanks, so that the shanks lie very close together, and when the nails are comparatively short.

Various attempts have been made to over- 40 come the difficulties encountered in separating and delivering such nails to the inserting mechanism of a loose nailing machine. In one construction the separating has been 45 effected by moving bodily sidewise what is in effect a small section of the raceway. It has been found, however, that this mode of

separating is satisfactory only in those machines in which the raceway extends transversely to the line of feed of the work, since 50 it is usually desirable that the fastenings be inserted with the greatest dimension in cross-section lying crosswise to the edge of the work. In high speed loose nailing machines, however, the raceways have been ar- 55 ranged so that they extend substantially parallel to the line of feed of the work in order that a raceway sufficiently long to supply nails to the inserting mechanism may be provided and, further, in order that 60 the raceway may not interfere with the other mechanisms.

Since it is substantially requisite that rectangular or oblong nails or other fastenings be guided in the raceway with their 65 longer transverse dimensions extending lengthwise of the raceway, it is necessary in separating a fastening from the line in the raceway, either by the means just described or by the ordinary means, to effect 70 a subsequent partial rotation of the fastening as it is delivered to the inserting mechanism in order to bring its longer dimension in cross-section into a position in which it will extend at right angles to the edge of 75 the work.

A further object of the invention therefore is so to improve the guiding and separating means in a loose nailing machine that a long raceway mounted at one side of 80 the inserting mechanism may be employed, and that nevertheless the nail or other fastening may be delivered to the inserting mechanism in the desired transverse relation to the edge of the work preferably 85 without turning it during the delivering operation.

In the preferred embodiment of the invention the foregoing objects are attained by providing a raceway which is curved side- 90 ways in such manner as to cause contiguous nails or other fastenings in the raceway so to move about their own axes as to produce a gap between them for the entry of a sep-

arator. Conveniently the raceway is curved to such an extent as not only to produce the gap aforesaid but in addition to aline the nail with the path of the separator in order 5 that the latter may impel the nail in the direction of its motion. By thus curving the raceway sideways it is possible not only to aline the endmost nail with the path of the separator but also to insure that the 10 nails by bearing against the opposite sides of the raceway throughout their traverse of the curve shall be constantly under control whereby they can be delivered into a desired position with certainty and precision.

15 The nail or other fastening as it is separated from the others in the raceway may be pushed by the separator directly into the path of the driver or, as in the preferred embodiment of the invention, it may be carried 20 into the driving position by a transferrer into which it is pushed by the separator. An important feature of the invention, therefore, is nail delivering mechanism comprising means to impel a rectangular or oblong nail or other fastening from a raceway 25 or other guiding means into a receiver, preferably yieldingly contracted, which preferably grips the nail and transfers it to the driving position.

30 The invention also comprises an improved nail transferring device. This device is provided with a pivoted or other yielding part which not only guides and grips a nail while it is being driven but yields sufficiently to 35 permit the transerrer to be moved toward its nail receiving position without waiting for the withdrawal of the driver.

A preferred embodiment of the invention will now be described with the aid of the 40 accompanying drawings, but it is to be understood that the invention is not necessarily limited to the precise construction and arrangement of parts as shown, as this embodiment of the invention is merely by way 45 of example and is capable of considerable variation without departing from the nature of the invention.

Figure 1 is a front elevation of those parts 50 of a nailing machine embodying the invention with which the invention is immediately associated; Fig. 2 is a plan with parts in section of the mechanism shown in Fig. 1; Fig. 3 is a plan drawn to a larger scale than Figs. 1 and 2 of the end portion of the nail raceway 55 and certain parts co-operating therewith; Fig. 4 is a view similar to Fig. 3, but showing the said parts in a different operative position; Fig. 5 is a view of the end of the separator lever, and Fig. 6 is a perspective view of a nail which the mechanism of this invention is especially adapted to handle.

The machine to which this invention is applied may conveniently be of the type dis-

closed in the United States Patent to L. 65 Goddu, 490,624, January 24, 1893, the awl bar 2 carrying the awl 4, the driver bar 6 carrying the driver 8 and the separator lever 10 being operated by the means and in substantially the manner disclosed in said 70 patent.

The machine illustrated in the drawings includes a raceway 12 into which the nails are fed from any suitable hopper or other suitable fastening container and down which they travel to the nail separating mechanism. This mechanism comprises a push off piece or separator 14 carried by the separator lever 10 and arranged to push the nail into a recess or slot 16 in a carrier or transferrer 18 by which it is transferred into a position from which it is driven by the driver 8 through the throat of the machine into the work. According to this embodiment of the invention the nail raceway 12, 85 instead of being straight throughout its length, as has been the ordinary construction, terminates in a bent portion 20 so that the lowermost nail will be turned axially through an angle of approximately 90° before being engaged by the push off piece or separator 14 and moved into the recess 16 90 in the carrier or transerrer 18. By thus turning the endmost nail in the raceway relatively to the next succeeding nail a gap 95 is produced between the said nails for the entry of the separator, and in the construction illustrated this position of the parts is such that the endmost nail is alined with the path of the separator and is impelled by the 100 separator in the direction of that path. By this arrangement the separation of a single nail from its companions in the raceway is insured, and the nail is guided accurately along the raceway and is delivered with certainty therefrom into the recess 16 in the transerrer 18.

From the foregoing it will be noted that an oblong nail, like that illustrated in Fig. 6, which enters the raceway with its shorter 110 transverse dimension crosswise to the direction of movement is turned axially through a right angle before being delivered into driving position so that it can be driven into the stock with its longer transverse dimension 115 crosswise to the margin of the sole which is fed in a direction parallel to the line of travel of the nails in the main portion of the raceway. The push off piece or separator 14 and the end of the lever 10 to which it is 120 attached are illustrated in detail in Fig. 3.

The carrier or transerrer 18 forms part of a cylindrical slide 22 that is adapted to slide within a bearing 24 secured to the side of the raceway 12. The slide 22 is provided with a shoulder 26 against which one end of a spring 28 abuts, said spring surrounding the slide. The other end of the spring 28

bears against a collar 30 formed in the bearing 24. The slide 22 is thus forced outwardly from the bearing by the spring 28, the extent of movement being adjustable by 5 lock nuts 32 and 34 held against the end of the bearing and screwed upon the end of the slide 22 which projects beyond the collar 30 of the bearing. This adjustment of the traverse of the slide 22 provides for adjustment 10 of the position to which the carrier 18 is moved for the purpose of enabling the recess 16 in the carrier to be brought into proper alignment with the driver 8 to enable the nail to be driven. The nail transferrer 15 18 is operated so as to pull back against the action of the spring 28 to bring it into its nail receiving position by a pendent lever 36 which is pivoted at 38 upon the head 40 of the machine and which receives motion from 20 a tappet roll 42 carried upon the awl bar 2. The pendent lever 36 comprises an extension piece 44 that acts on the nail trans- ferrer 18.

Means for adjustment between the lever 36 25 and the transferrer 18 is provided for the purpose of insuring that the transferrer shall be returned into correct position to receive the nails from the raceway. This adjustment can be obtained if desired, as illus- 30 trated in the accompanying drawings, in which the extension piece is formed integrally with the lever 36 and engages a circular block 46 which is eccentrically mounted upon the transferrer 18 and may there- fore be turned to vary the position of the transferrer with relation to the lever 36.

The pendent lever 36 is operated by the vertical movement of the tappet roll 42 on the awl bar 2 through a projecting part 48 40 of the pendent lever 36; the said part being provided with a surface that is engaged by the tappet roll. The aperture or recess 16 in the nail transferrer 18 preferably conforms to the shape of the nail, and one side 45 of this recess—the one nearer the driver 8—is constituted by a hinged flap 50 that is pivoted upon the carrier. This flap is normally held shut by means of a coiled spring 52 that surrounds the pivot upon which the 50 flap is pivoted and has one end engaging the flap and the other acting against the trans- ferrer. This arrangement of the hinged flap insures that when the nail is pushed into the recess 16 the nail will be held with a yield- 55 ing grip by the hinged flap, and thus re- tained while being transferred into alignment with the nail driver 8 where it will be driven by said driver through the ordinary nail throat into the work. The spring flap 60 50 also enables the nail transferrer 18 to be returned immediately to its nail receiving position by the pendent lever 36 without waiting for the driver to be withdrawn, as when the transferrer is moved the hinged

flap will be turned outwardly against its 65 spring, see Fig. 4, and thus ride over the driver 8 and permit the transferrer to move.

In Fig. 6 is shown in perspective a type of nail which this invention is especially adapted to handle. This type of nail is 70 used quite generally in England for the purpose hereinabove pointed out and is there known as the "Cutlan bill" nail from the name of its inventor, the term "bill nail" being applied to short, stumpy nails 75 of this type.

The operation of the embodiment of the invention hereinabove described will be understood from the foregoing description of the parts and their method of acting, but 80 for the sake of clearness may be briefly recapitulated as follows: The nails travel down the raceway 12 and the lowermost one passes around the bent portion 20 there- of so as to turn through approximately a 85 right angle when it is engaged by the push off piece 14 by which it is pushed along the raceway into the recess 16 in the carrier or transferrer 18. In the recess the nail is held by the spring-pressed flap 50. By the lift- 90 ing of the awl bar 2 the tappet roll 42 is removed from contact with the part 48 of the lever 36, thereby permitting the trans- ferrer spring 28 to move the transferrer 18 to bring the nail into the nail throat and 95 beneath the driver 8 which then operates to drive it into the work. The next descent of the awl bar 2 causes the return of the trans- ferrer 18 to its initial position ready 100 for the reception of the next nail, by the ac- tion of the part 48 upon the tappet roll 42.

In the foregoing description and in the following claims the raceway is referred to as "parallel to the line of feed of the work." In this expression, as well as in other ex- 105 pressions herein in which the term "par- allel" is used, parallelism of the vertical planes of location rather than actual line parallelism is intended.

Having described our invention, what we 110 claim as new and desire to secure by Letters Patent of the United States is:—

1. A machine of the class described, hav- 115 ing, in combination, fastening inserting mechanism, a continuous fastening raceway extending substantially parallel to the direction of feed of the work past said inserting mechanism but having at its lower end a sec- 120 tion extending substantially transverse to the direction of feed of the work, whereby the fastenings are each turned through an angle of 90° and means for delivering a fastening from said raceway to said inserting mecha- 125 nism constructed to transfer said fastening first along said raceway section and then along the path of feed of the work while maintaining it in axial parallelism.

2. A machine of the class described,

having, in combination, mechanism for inserting fastenings which are rectangular in cross-section, a raceway arranged to conduct the fastenings in a line with their transverse dimensions at right angles to the desired inserting position and constructed to turn each fastening about its longitudinal axis through an angle of substantially 90° before its delivery to the inserting mechanism, 5 and means for delivering the endmost fastening to the inserting mechanism arranged to enter the gap between the endmost two fastenings caused by the axial turning of said endmost fastening.

15 3. A machine of the class described, having, in combination, mechanism for inserting fastenings, a raceway and a separator arranged to move transversely to the main portion of said raceway, said race- 20 way comprising a portion at its delivery end so curved as to cause contiguous fastenings to so move about their own longitudinal axes as to produce a gap between them for the entry of said separator and so constructed 25 and arranged as not only to produce the gap aforesaid but in addition to align the fastening to be separated with the path of the separator and to maintain said fastening with its transverse dimensions at right 30 angles to their position in the main part of the raceway, and means for operating said separator to cause it to propel the fastening along its path of movement in axial parallelism with the other fastenings in the 35 raceway.

4. In a machine of the class described, a raceway for fastenings of oblong cross-section having at the forward end a section curved sidewise and so constructed that the 40 fastenings bear against opposite sides of the raceway in the traverse of the curve whereby they are turned about their longitudinal axes to produce a gap between the endmost two fastenings in the raceway for the entry 45 of a separator, and a separator arranged to enter the gap and propel the endmost fastening bodily along the raceway in the direction of movement of said separator, the fastenings being free to gravitate down said 50 raceway into fastening delivering position.

5. In a machine of the class described, a reciprocating fastening transferrer, a race- 55 way the general direction of which corresponds to that in which reciprocation of the transferrer takes place, said raceway being curved sidewise in proximity to said transferrer and a separator the path of which is tangential to said curve and transverse to the direction of movement of said trans- 60 ferrer.

6. A machine of the class described, having, in combination, mechanism for inserting fastenings, a raceway presenting the nails in a plane substantially parallel to the

path of feed of the work past said inserting 65 mechanism, but laterally offset from said path, a fastening transferrer having a trans- 70 ferring movement parallel to said plane and in the line of the work feed, and means for pushing the endmost fastening of those in 75 the line in said raceway into said trans- ferrer.

7. A machine of the class described, hav- 80 ing, in combination, inserting mechanism, a raceway curved at its delivery end, a trans- 85 ferrer for transferring the endmost fasten- 90 ing in the raceway to the inserting mech- 95 aism, and means for pushing said fastening into said transferrer, said transferrer being constructed and arranged to close the end 100 of said raceway during its fastening trans- ferring operation.

8. A machine of the class described, hav- 105 ing, in combination, fastening inserting mechanism comprising a fastening driver, 110 an awl and an awl bar, a raceway and a trans- 115 ferrer for transferring a fastening from the raceway to the inserting mechanism, said transferrer being constructed to hold the fastening in driving position dur- 120 ing the inserting operation, and means controlled by the awl bar during the work penetrat- 125 ing movement of the awl for returning said transferrer toward fastening receiving position, said transferrer having provision 130 whereby it may be returned toward fasten- 135 ing receiving position after the fastening has been driven and before the driver is raised.

9. A machine of the class described, hav- 140 ing, in combination, fastening inserting mechanism comprising a driver, an awl and 145 an awl bar, a raceway and a trans- 150 ferrer arranged to transfer a fastening from the raceway to the inserting mechanism, and means controlled by the awl bar during the work penetrat- 155 ing movement of the awl for returning said transferrer toward fastening receiving position, said transferrer being provided with a yielding part which grips 160 and guides the fastening during the insert- 165 ing operation and permits the trans- 170 ferrer to be returned to fastening receiving position after the fastening has been driven and before the driver is raised.

10. A machine of the class described, hav- 175 ing, in combination, a raceway, an awl, an awl bar and a driver, said awl operating to feed the work into position to receive a fastening driven by said driver, and means con- 180 trolled by the awl bar as the awl is with- 185 drawn from the work for transferring the fastening from the raceway to said driver.

11. A machine of the class described, hav- 190 ing, in combination, a reciprocating fasten- 195 ing transferrer yieldingly pressed normally in the fastening delivering direction, an awl and awl bar and means operated from said

awl bar during its awl driving movement for restoring said transferrer to its fastening receiving position.

12. A machine of the class described, having, in combination, a raceway, an awl, and a driver, a reciprocating transferrer arranged to transfer a fastening from said raceway into position to be driven by said driver, yielding means tending normally to move said transferrer in its fastening delivering direction and adjustable means oper-

ating in timed relation to the movement of said awl for restoring said transferrer to its fastening receiving position.

In testimony whereof we have signed our 15 names to this specification in the presence of two subscribing witnesses.
